UNITED STATES PATENT OFFICE.

GEORGE C. CHERBONNIER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-DOOR-LOCKING MECHANISM.

1,244,698.

Specification of Letters Patent. Patented Oct. 30, 1917.

Application filed February 1, 1917. Serial No. 145,878.

To all whom it may concern:

Be it known that I, GEORGE C. CHERBONNIER, residing at city of St. Louis, State of Missouri, and being a citizen of the United States, have invented certain new and useful Improvements in Car-Door-Locking Mechanism, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Figure 1 is a fragmentary elevational view of a portion of the side of a car showing the improved lock applied thereto;

25 Fig. 2 is a vertical section transversely of Fig. 1, being taken on line 2—2 of that figure;

30 Fig. 3 is another transverse sectional view, the same being taken on line 3—3 of Fig. 1 and being observed in the direction of the arrows;

35 Fig. 4 is a horizontal section taken on the line 4—4 of Fig. 1 looking downwardly;

Fig. 5 is an elevation of one side of the peculiar bushing employed in the door lock;

40 Fig. 6 is a view showing parts of the floor lock in separated relation to more clearly illustrate the conformation of each; and

Fig. 7 is a view on a smaller scale similar to and more extensive than Fig. 1 and showing a plurality of door locks applied to the side of the car in connection with a number of doors.

45 This invention concerns door locking mechanism and is adapted to the purpose of locking car doors which may be arranged in any suitable manner in a railway car.

A very useful employment of the invention is in connection with cars having vertically suspended doors placed in succession along the car sides, as in a ballast car, the 50 doors having their bottom edges just above the car floor. Side sills may underlie the floor near the side edges thereof and may each be used as a support for a plurality of door locks securely mounted thereon in position to hold the doors closed.

It is an object to provide an operating shaft for the set of door locks supported by the sill or other underframe member, and also to position the locks and the operating shaft therefor on the inner side of the underframe member and beneath the car floor in a highly protected location. At the same time, the portions of the door locks that are intended to hold the doors closed are, where the construction makes it advisable, to be 60 projected through the underframe member to reach door-engaging points and to be freely operable through that member. Convenience in regulating the discharge of the load carried by the car is provided for, and 65 all of the locks may be simultaneously operable to permit a quick clearing of the car. When it is wished to expeditiously discharge but a portion of the load, or portions one at 70 a time at different locations, no obstacle to 75 so doing is encountered as each of the locks is readily operable independently of the operating shaft or any of the other locks.

Various other features of merit, including the peculiar construction and operation of 80 the locks themselves will become disclosed hereinafter and come within the scope and spirit of the present invention.

Referring to the drawings, 10 represents a member of the underframe and in the 85 present instance is illustrated as being a channel-shaped side sill. Riveted to the outer side of the web of sill 10 and extending upwardly for any suitable distance, are side posts 9, shown in Fig. 4 to be of U or J 90 shape in cross-section. Side posts 9 are suitably spaced along the sides of the car and interposed between them are vertically arranged doors 11, these doors being pivoted at any convenient points (not shown), but 95 preferably at their upper portions so as to swing outwardly from the side of the car when it is desired to discharge lading.

As shown, the doors are reinforced by metallic members 8 to which are secured 100 hasps 28. The latter are arranged on the outer side of the door and extend below the same to lap the car floor 7 and the upper portion of the underframe members or side sills 10.

105 As shown in Fig. 7, the hasps are arranged longitudinally of sill 10 at suitably spaced locations, and co-operating with each hasp is a door lock, an operating shaft 18 being common to all the door locks on one 110

side of the car and adapted to operate them simultaneously.

The door locks are secured to the inner side of sill 10 and each comprises the elements illustrated in Fig. 6, wherein 12 is a bracket adapted for direct attachment to sill 10 and having a flange extending inwardly from the inner face of sill 10. Said flange is provided with an aperture 12^a through which is inserted a part of the cylindrical portion 13 of a lock bushing 14, the wall of aperture 12^a forming a bearing for said bushing.

The end of bushing 14 that does not enter the bearing so formed by the flange of bracket 12 is provided with a peculiar flange which is L-shaped in one of its cross sections and a portion 19 of which extends parallel with the axis of the cylindrical bushing portion 13. The inner face 20 of portion 19 is curved and concentric with the convex surface of cylindrical portion 13 from which it is spaced a sufficient distance to provide a recess for receiving the hooked end 22^a of the door latch 22.

In assembling the door locks, the brackets 12 are riveted or otherwise secured to the inner side of sill 10 and are appropriately spaced therealong to be in proper relation with the successively arranged doors 11 as, for example, shown in Fig. 7. An operating shaft 18 extends longitudinally of sill 10, being spaced inwardly from the inner face of sill 10 so as to pass through bearing apertures 12^a in the brackets 12, said shaft being threaded through a square hole 17 in the cylindrical portion 13 of each door lock bushing 14, said bushings at first being separated from brackets 12. A latch 22 is interposed between bracket 12 and bushing 14 of each door lock after which the bushing 14 is moved toward bracket 12 so that its cylindrical portion 13 passes through the hooked end 22^a of latch 22 to pass through and beyond the flange of bracket 12 that contains the bearing aperture 12^a. A cotter pin 15 is then inserted through holes 15^a in the cylindrical bushing portion 13 and passes through the squared or non-circular shaft 18.

When the parts are so combined, one face of the flange containing the bearing aperture 12^a, the convex surfaces of the bushing cylindrical portion 13 and the bushing flange 55 curved face 20 and also a flat face of the bushing flange which is at a right angle to the curved face 20, form a passageway through which the curved end 22^a of latch 22 extends and is adapted to inescapably turn about 60 the bushing cylindrical portion 13.

The width of the passageway just described is very slightly in excess of the width of latch 22, and this width is preserved by the locking of bushing 14 to operating shaft 18 by means of cotter pin 15.

Said width is also determined by faces of lugs 16 and 16^a projecting from and preferably integral with cylindrical bushing portion 13, said lugs having faces bearing against the contiguous face of the flange of bracket 12 that contains the bearing aperture 12^a.

Latch 22 extends outwardly from its hook-like end portion 22^a and passes through a slot in the web of channel 10, continuing 70 therebeyond a suitable distance, as shown in Fig. 2. The outer end of latch 22 is wedge-shaped, being beveled on its under side to produce an engagement surface 29, which extends from the nose of said latch rearwardly and downwardly nearly to the shoulder 27 at one end of the wedge-shaped portion of said latch. On the under side of the latch 22, intermediate shoulder 27 and the inner end 22^a of said latch, and preferably within the hook-shaped portion, is another engagement-surface 25.

Lug 16 extending from cylindrical portion 13 of bushing 14 also has a beveled face 26 which is adapted to engage contact surface 25 of latch 22 and to ride therealong when bushing 14 is rotated in such manner as to raise said latch. Lifting latch 22 in this manner causes its shoulder 27 to disengage a shoulder formed by a bottom cross 90 bar in the hasp 28 carried by the door 11 with which the particular lock under consideration is associated. Said hasp 28 is provided with a web containing a slot or perforation through which the outer wedge-shaped end of latch 22 projects when its shoulder 27 is in engagement with the cross bar of hasp 28 to hold the door closed. After the raising of latch 22, as described, to disengage shoulder 27 from hasp 28, the 105 door 11 is adapted to swing outwardly under the influence of the lading carried by the car. After the lading discharge, the door may then be closed by simply pushing it back to assume its vertical position, whereupon the cross bar of hasp 28 will come into contact with engagement surface 29 on the under side of the outer end of latch 22, causing said latch to rise until its shoulder 27 has passed over the hasp cross bar, after 110 which said latch 22 drops by gravity to the position shown in Fig. 2, again locking the door in position.

All of the locks applied to the same side sill or other underframing member are operable simultaneously by turning the operating shaft 18 clockwise, when each lock of the set will be operated in the manner set forth with respect to one of the locks. Operating shaft 18 may be reversed to a certain 125 degree after the release of the doors, it then being possible to close any of the doors independently of the others.

Should it be desired to open only one or more than one but not all of the doors, this 130

may be readily accomplished by lifting the latches 22 of the locks associated with that or those doors manually, and without actuating the operating shaft 18.

- 5 As the hooked end 22^a of the latch of each of the doors is revolvably mounted about the cylindrical portion 13 of bushing 14 and as it further lies upon and is controlled in opening by the lug or cam 16, it 10 is obvious that the latch of each door is operable independently of shaft 18.

It is to be noted that in Fig. 2 the end or terminal face 24 of the hook portion 22^a of the latch is spaced from the opposing face 15 of lug 16^a. In consequence of the resultant lost motion, there is no opposition to the turning of latch 22 to permit the independent raising thereof.

Assuming that the lading of the car has 20 been discharged and that the doors have been pushed inwardly to accomplish their automatic closure by having the shoulders 27 of the latches 22 engage the shoulders of the hasps 28, the operating shaft 18 may 25 be further turned counterclockwise to move the lug 16^a of the bushing 14 of each door lock into engagement with the terminal face 24 of the inner or hook end of the latch 22. Due to such placing of the lugs 16^a of 30 all the door locks, said latches 22 thereof are locked in their door-retaining positions and may not be independently raised, accidentally or otherwise, to effect the release of any or all of the doors.

35 Because of the mounting of the door locks on the inner side of the side sills and underneath the floor, said locks and the operating shaft therefor are in a highly protected position.

40 What I claim is:

1. In combination in a car or other structure having door openings, doors adapted to close the openings, a set of suitably mounted door locks and a rockable member 45 adapted to operate said set of locks, said locks being independently operable.

2. In combination in a car or other structure having door openings, doors adapted to close the openings, suitably mounted 50 door locks provided with door-locking latches to and from which said doors are movable, said latches being hooked into the structure of said locks and a door lock-operating shaft adapted to operate said locks 55 to actuate said latches.

3. In combination in a car or other structure having door openings, doors adapted to close the openings, door locks mounted on said structure comprising members and 60 latches, the latter having hook portions interposed between said members, said members co-operating to pivotally support said latches, a door-lock-operating shaft adapted to cause the actuation of said latches, 65 the latches being independently operable.

4. In combination in a car or other structure, doors arranged in succession, door locks for said doors comprising associated members inserted one into the other, latches provided with hook portions interposed between 70 associated members pivotally retained by the insertion-effecting portions of said members and a door-lock-operating shaft, said latches being operable thereby and also independently thereof. 75

5. In combination in a car, a sill, doors adapted to close in proximity thereto, door locks comprising stationary members mounted on said sill, oscillatory members pivotally combined therewith and latches 80 pivotally mounted on said oscillatory members and maintained by the latter members for co-operative relation with said doors and an operating shaft for said door locks.

6. In combination in a railway car, a sill, 85 doors adapted to close in proximity thereto, door locks projecting from both sides of said sill adapted to hold said doors closed, each lock being independently operable and an operating shaft for said door locks adapted to operate the same simultaneously.

7. In combination in a railway car, a sill, 90 doors adapted to close in proximity thereto, door locks projecting from the sides of said sill adapted to hold said doors closed and an operating shaft for said door locks, said locks being operable independently of said shaft.

8. In combination in a railway car, a sill, 95 doors adapted to close near said sill, door locks on one side of said sill extending through the same and adapted to hold said doors closed and an operating shaft for and rockably held by said door locks. 100

9. In combination in a car, a sill, doors adapted to close near the same, extensions from said doors, door locks mounted on said sill extending therethrough and therebeyond and adapted to engage said door 110 extensions to hold said doors closed and an operating shaft operably connected with said locks.

10. In combination in a car, a sill, a floor, 115 a door, a door lock supported to be protected by said sill and floor and extending to hold said door closed and an operating shaft operably connected with said lock and protected by said sill and floor, the door-holding lock portion being movable independently of said shaft to release said door. 120

11. In combination in a railway car, a side sill, doors adapted to open away from said sill, door locks extending beyond the outer side of said sill operable to release one or a plurality of doors as desired, and an operating shaft located inside of said sill operably connected with said door locks. 125

12. In combination in a car, a sill, a door adapted to open away therefrom, a door 130

- lock comprising a bracket secured to said sill, an oscillatory member having a bearing in said bracket, a door-retaining latch having a hook-like end held captive between 5 said bracket and oscillatory member and an operating shaft operably connected with said door lock and extending through said oscillatory member.
13. In combination in a car, an under-frame member, a door adapted to close in proximity thereto, a door lock comprising a fixedly positioned bracket, an oscillatory member provided with a pivotal portion bearing in said bracket, said member and bracket forming a curved passageway in said lock and a latch having a hooked end adapted to inescapably travel in the passageway and operating means for said oscillatory member, the latter being adapted to 20 operate said latch.
14. In combination in a car, an under-frame member, a door adapted to close near the same, a door lock comprising an apertured bracket fixedly positioned with reference to said member, a bushing having a cylindrical portion revolvably mounted in a bracket aperture, a latch retained between said bracket and bushing, said latch and bracket having portions substantially concentric with the bushing cylindrical portion and means on the latter adapted to actuate said latch and an operating shaft extending through said bushing.
15. In combination in mechanism of the class described, a fixedly positioned bracket containing a bearing, a bushing comprising a cylindrical portion seated in said bearing, a portion having a face spaced from and concentric with said cylindrical portion and 40 latch-actuating-and-controlling portions, a door-latch having a hook-like end retained and adapted to turn between said cylindrical and concentric-faced bushing portions and an operating shaft drivingly combined with 45 said bushing.
16. In combination in mechanism of the class described, a bracket, a bushing comprising a main portion extending through and adapted to turn in said bracket, a portion co-acting with said main portion and bracket to form a curved passageway and latch-actuating-and-controlling portions, a door-latch retained and adapted to travel in the passageway, an operating shaft passing drivingly through said bushing and means preserving the association of the parts.
17. In combination in mechanism of the class described, a bracket, a bushing comprising a main portion extending through and adapted to turn in said bracket, a portion co-acting with said main portion and bracket to form a curved passageway and latch-actuating-and-controlling portions, a door-latch retained and adapted to travel 60 in the passageway, an operating shaft passing drivingly through said bushing and means preserving the association of the parts, said latch being independently operable at will.
18. In combination in mechanism of the class described, a bracket, a bushing comprising a main portion extending through and adapted to turn in said bracket, a portion co-acting with said main portion and 70 bracket to form a curved passageway and latch-actuating-and-controlling portions, a door-latch retained and adapted to travel in the passageway, an operating shaft passing drivingly through said bushing and means preserving the association of the parts, said latch being independently operable at will and said latch-controlling portions being adapted to lock said latch.
19. In combination in mechanism of the class described, a bracket, a bushing revolvably mounted therein, an extension from said bushing, a door-latch having a hook portion mounted to turn on said bushing and also provided with an engagement portion, 80 means maintaining said latch hook portion and bushing in co-operative relation and means adapted to turn said bushing and cause said extension to engage the hook engagement portion to actuate said latch.
20. In combination in car or other structure having doors, a door member, a bracket, a bushing revolvably mounted therein, an extension from said bushing, a door latch having an open portion mounted to turn on said bushing and also having differently located engagement surfaces, means holding said latch open portion and bushing from separation, and means to operate said bushing to cause said extension to engage one of said 105 surfaces to actuate said latch, said door member being adapted to engage another of said surfaces and actuate said latch.
- In witness whereof I have hereunto set my hand in the presence of two witnesses. 110
